GARMENT HANGER

Harriet C. Turner and James H. McGann, Los Angeles, Calif.

Application July 17, 1942, Serial No. 451,248

5. Claims. (61, 223—87.)

This invention relates generally to apparel and more particularly to hangers for holding garments when not in use.

An object of this invention is to provide a garment hanger which is structurally characterized in a manner to utilize relatively cheap and plentiful materials in its manufacture; and to produce a strong durable device of simple construction capable of being rapidly manufactured at a low cost.

Another object of this invention is to provide a garment hanger composed of a minimum number of parts of cardboard or other paper or cheap fibre derivative materials capable of being rapidly produced by suitable dies and easily assembled by unskilled labor to form a very serviceable structure adequately durable for repeated use in holding various types of male and female garments.

With these and other objects in view, the invention resides in the combinations and arrangements of parts as set forth in the following specification and particularly pointed out in the appended claims.

In the accompanying drawing,

Figure 1 is a view in elevation partly broken away, of one form of garment hanger embodying this invention, and looking at the obverse side of the hanger;

Figure 2 is a view similar to Figure 1 and showing the reverse side of the hanger;

Figure 3 is a transverse sectional view taken on the line 3—3 of Figure 1 and looking in the direction of the arrows;

Figure 4 is a view of the blank from which the body portion of the hanger is formed;

Figure 5 is a view similar to Figure 1, and showing a modified form of garment hanger particularly adapted for use as a combined coat and trousers hanger;

Figure 6 is a view similar to Figure 5 and showing the reverse side of the garment hanger;

Figure 7 is a transverse sectional view taken on the line 7—7 of Figure 5 and looking in the direction of the arrows.

Referring specifically to the drawing and particularly to Figures 1 to 4 inclusive, this form of garment hanger comprises an elongated body member 10 preferably constructed of cardboard of the requisite stiffness from the blank B shown in Figure 4 which is foldable along the lines 11 and 12 to provide side walls 13 and 14, the former of which is continuous from one end of the body member to the other. Due to the angularity between the fold lines 11 and 12, the side wall 14

is formed in two portions, which, in the folded or set up position of the body member shown in Figures 1, 2 and 3, abut at confronting edges 15 and 16 of the blank B along a vertical or transverse medial line to form a tight joint 17 (Figure 2).

At the juncture of the fold lines 11 and 12 in the blank B, a notch 18 is formed to leave a slot 19 in the body member when folded, for the reception of a hook 20 on a member 21 constructed of binder board or other suitable strong and rigid material. At the base of the hook 20, the member 21 is formed to provide lateral anchoring projections or wings 22 fitting closely against the connecting bight between the side walls 13 and 14 and confined between the latter.

A reinforcing member or filler 23 of corrugated carton board or other suitable material of a thickness corresponding to that of the hook member 21, is cut out at 24 to receive the base of the member 21 and is of a contour to fit against the connecting bight between the walls 13 and 14 and to be substantially co-extensive in length with the body member 10. By means of a suitable adhesive 25 such as glue or paste, the side walls 13 and 14 are rigidly secured to the filler 23 and to the hook member 21 so as to produce an inexpensive, durable and lightweight structure capable of satisfactorily withstanding repeated use.

Reference will now be had to Figures 5, 6 and 7 illustrating a modified form of garment hanger the body member 10a of which differs essentially from the body member 10 in being provided with a longitudinal slot 30 to provide a crossbar 31 on which trousers can be hung. Medially of the body member, the top portion of the slot 30 is widened to provide a convenient hand space 32 to facilitate the application and removal of the trousers.

A hook member 21a is identical in construction to the hook member 21, whereas a reinforcing member or filler 23a preferably of corrugated carton board is provided with a slot 33 identical in contour to that of the slot 30 in the body member 10a.

One side wall 13a of the body member is continuous, whereas the other side wall 14a is in two portions which terminate along the top and ends of the slot 30 as shown in Figure 5, and abut along the medial line to form a tight joint 17a (Figure 6). In blanking out the slot 30, flaps 35 and 36 are formed. The flap 35 is folded over the crossbar-forming portion 31 of the filler 23a, and

the flap 36 is folded over the filler 23a beneath the abutting portions of the side wall 14a, all as clearly shown in Figures 6 and 7.

A suitable adhesive is employed to rigidly secure the side walls 13a and 14a to the filler 23a and to the hook member 21a, and to secure the flaps 35 and 36 to the filler member, whereby to produce a combined coat and troweler hanger of inexpensive, lightweight construction, which is amply durable to withstand ordinary use for an indefinite period of time.

We claim:

1. A garment hanger comprising: an elongated body member of sheet material folded to provide spaced side walls, and having a longitudinal slot to provide a crossbar along its bottom edge; a hook member projecting from the body member and having an anchoring portion secured between said walls; and a reinforcing filler member secured between said walls and having a portion forming part of said crossbar.

2. A garment hanger comprising: an elongated body member of sheet material folded to provide spaced side walls, and having a longitudinal slot to provide a crossbar along its bottom edge; a hook member projecting from the body member and having an anchoring portion secured between said walls; and a reinforcing filler member secured between said walls and having a portion forming part of said crossbar; one of said walls having a flap folded over and secured to said crossbar-forming portion of the filler member.

3. A garment hanger comprising: an elongated body member of sheet material folded upon itself to provide one continuous side wall and a second wall in two portions defining a transverse joint along a line medially of the body member, while leaving a slot at the upper edge of the latter; said first side wall having a longitudinal slot to form a crossbar along the bottom edge of the member, with the second said wall terminating at the upper edge of and extending across the ends of said longitudinal slot; a hook member of sheet material having a hook projecting through the

first slot, and lateral anchoring projections secured between said walls; a filler member secured between said walls and having a portion forming part of said crossbar; a flap extending from said first wall through the longitudinal slot over the crossbar-forming portion of said filler member and secured to the latter; said longitudinal slot being widened medially along its upper edge to provide a hand space; and a flap extending from said first wall through the hand space and over the filler member between the latter and said two portions of the second said wall.

4. A garment hanger comprising: an elongated body member of sheet material folded upon itself to provide one continuous side wall and a second wall in two portions defining a transverse butt joint along a line medially of the body member, said two portions being disposed in co-planar relationship to provide a smooth exterior surface on the second said wall while leaving a slot at the upper edge of the body member; a hook member of sheet material having a hook projecting through said slot, and lateral anchoring projections secured between said walls; and a reinforcing filler of sheet material between said walls to which the latter are secured, and being provided with a cut out portion receiving said anchoring projections to co-act therewith in rigidly supporting the hook member against displacement relative to the body member.

5. A garment hanger comprising: an elongated body member of sheet material folded to provide spaced side walls co-extensive in length with the member and leaving a slot along the fold of said walls; a hook member of sheet material projecting through said slot and having lateral anchoring projections disposed between said walls; and a reinforcing filler member of sheet material secured between said walls and having a cut out in which said projections fit for co-action in rigidly holding the hook member against displacement.
